SAFETY RAZOR

Glenn T. Randol, Mountain Lake Park, Md.

Application June 24, 1950, Serial No. 170,145

9 Claims. (Cl. 30—51)

1

The present invention relates to a safety razor and more particularly to a razor which is provided with a spring-clip type head for retaining a razor blade in easily attached, readily removed cutting position.

The safety razor art has been highly developed in the attempt to provide an economically produced, readily employed razor which is mechanically simple, and capable of securely clamping a blade in cutting position while still accommodating ready insertion and removal of the blade. The utilization of spring-urged clamping means has been proposed in the prior art, but the prior art razors generally employ a coil or tension spring means which is separate and apart from the blade clamping means and housing. Also the prior art devices of this type usually mask a portion of the blade cutting edge by the clamping members, thereby reducing the effective blade cutting length, and also it is necessary to manually grasp the blade to remove the same from the clamping means.

The present invention now provides an extremely simple, readily employed safety razor which is provided with a spring-clip blade-retaining head in which the head itself possesses the tension necessary to retain the blade in cutting position, while accommodating removal of the blade after use by mere actuation of the blade retaining means and without the necessity of manually grasping the used blade. The blade cutting edge is entirely free of all obstruction by the blade retaining means so that the entire cutting edge of the blade is effective for cutting.

More particularly, the present invention utilizes a clamping blade head in the form of a substantially cylindrical or semi-cylindrical spring clip having a longitudinal slot through which the blade cutting edge projects. A handle is secured to the head and carries a blade supporting surface provided with blade retaining lugs. A simple lever arm is positioned adjacent the handle for ready manual manipulation and is urged by the spring head into clamping relation with the blade and the handle to retain the blade therebetween. The lever arm preferably carries means engaging the blade adjacent the cutting edge thereof for urging the blade into seated relation with the handle portion lugs.

This extremely simple resilient blade clamping construction is capable of several modifications in which the split spring head may take non-cylindrical form, but the principle of operation remains the same in that the head itself resiliently urges blade clamping elements or members

2

toward one another into extended engagement with the blade to retain the same in position.

It is, therefore, a broad object of the present invention to provide a new and improved safety razor in which a blade is readily inserted and removed, which may be readily cleaned of beard and lather, and which may be manufactured at low cost to meet highly competitive market conditions.

A more specific object, related to the foregoing broad object of the present invention, is to produce a novel and improved safety razor comprising a blade retaining inherently springy head of substantially cylindrical or loop-shaped cross section, normally adapted to biasingly encompass a movable member and a fixed blade support member in clamping relation, said members accommodating the insertion of a blade therebetween upon manual movement of the movable member to deform the head against its inherent biasing action, and cooperable to adjust and retain the inserted blade in cutting position upon manual release of the movable member into normally biased clamping relation with the blade and fixed member.

Another important object of the present invention is to provide a safety razor provided with a spring-clip type head resiliently urging a pair of blade clamping members into clamping relation with a blade, one of the blade clamping members being formed as an attenuated handle which is manually actuatable against the pressure of the spring-clip head to accommodate insertion and removal of the blade.

It is a further important object of the present invention to provide an improved safety razor utilizing a split clip-type head with a blade extending beyond the head and resiliently retained therein by means of cooperative clamping elements interposed between the blade and the head and urged by the head into contact with the blade.

Still another important object of the present invention is to provide an improved safety razor in which a substantially cylindrical spring-type clip is utilized as the razor head to urge a pair of clamping elements into contact with a blade inserted within the head and retained by the clamping elements by means of cooperating lugs and camming extensions carried by the clamping members respectively and acting upon opposed portions of the blade to position and to retain the blade in cutting relation.

Other and further important objects of this invention will be apparent from the disclosures

in the specification and the accompanying drawings.

In the drawings:

Figure 1 is a rear perspective view of a razor of the present invention;

Figure 2 is a front perspective view of the razor of Fig. 1;

Figure 3 is a sectional view, with parts shown in elevation, taken along the plane III—III of Fig. 2;

Figure 4 is a sectional view taken along the plane IV—IV of Fig. 3;

Figure 5 is a sectional view taken along the plane V—V of Fig. 3;

Figure 6 is a sectional view, with parts shown in elevation, taken along the plane VI—VI of Fig. 3;

Figure 7 is a sectional view similar to Fig. 3 showing the spring-clip head open and a blade being removed;

Figure 8 is a sectional view taken along the plane VIII—VIII of Fig. 7;

Figure 9 is a sectional view similar to Fig. 5, showing the blade removed;

Figure 10 is an enlarged fragmentary elevational view of the blade retaining projection and adjacent portions of the blade clamping elements;

Figure 11 is an enlarged perspective view of a razor blade suitable for use with the razor of the present invention;

Figure 12 is a sectional view similar to Fig. 3 illustrating a modified form of razor;

Figure 13 is a view similar to Fig. 3 showing another modified form of razor of the present invention; and

Figure 14 is still another modified form of razor of the present invention.

Referring to the drawings:

In Figs. 1-3, reference numeral 20 refers generally to a razor of the present invention comprising an elongated handle 21 having a knurled or otherwise roughened peripheral gripping surface and a terminal reduced portion 22 from which projects a head supporting column 23.

As best shown in Fig. 3, the column 23 has integrally formed therein an arcuate intermediate portion 24 having a terminal downwardly and forwardly projecting support portion 25 constituting the fixed clamping element or member of the razor 10. The fixed clamping element 25 has a substantially plane intermediate portion from which a pair of longitudinally spaced lugs 26 are upwardly extruded with forwardly extending clips having upturned ends to form angular openings through which the butt edge of a razor blade 27 may be inserted to underlie the lug clips. It will be seen that the blade 27 when confined between the lugs 26 and the supporting portion 25 is in extended surface contact with the upper surface of the portion 25, with the blade rear butt edge being confined by the lugs. The portion 25 terminates in a downwardly offset guard portion 28 having an elongated slot 29 extending longitudinally therewith to underlie the cutting edge 30 of the blade 27. A terminal edge 31 of the guard 28 is deflected downwardly away from the blade edge 30 to serve as a guide.

The blade 27, hereinbefore referred to and best illustrated in Fig. 11, comprises a generally rectangular strip of metal provided with a longitudinal sharpened cutting edge 30 notched at each longitudinal end portion, as at 32 to provide longitudinal shoulders 33 extending substantially parallel to the sharpened edge 30 and in spaced relation thereto. The butt edge 34 of the blade

27 remote from the cutting edge 30 is not sharpened and is adapted for insertion beneath the lugs 26 struck from the fixed element 25.

The arcuate portion 24 of the column 23 has 5 secured to the inner surface thereof, as by rivets 35, a generally cylindrical split-type spring 36. The spring 36 is provided with a longitudinal slot 37 in spaced relation to the rivet 35, with one edge of the slot contacting the support portion 10 25 immediately rearwardly of the offset support portion 28. The head 36 is provided with a second slot 38 opposing the slot 37 and receiving there-through that end of the fixed element 25 remote from the lip 31. Thus, the fixed blade supporting element 25 extends radially across the interior of the cylindrical spring head 36, with the lugs 26 being enclosed by the spring head and lying at approximately the center of curvature thereof. The fixed element 25 is provided at each 20 of its longitudinal ends with an upturned end wall 30 which is centrally apertured, as at 40, each wall 39 being radially aligned with the corresponding extreme axial end of the spring head 36, as illustrated in Figs. 5 and 9.

A relatively movable clamping member or lever 41 is provided for cooperation with the fixed clamping handle post element 25 to clamp the blade 27 therebetween. The clamping lever 41 includes a forward ledge 42 overlying the blade 30 27 rearwardly of the cutting edge 40, an upwardly displaced central portion 43 extending across the interior of the spring head 36, and an elongated extension 44 extending through an aperture 45 to project beyond the spring head. That portion 35 of the clamping arm projecting beyond the spring head is arcuately deformed to lie in closely spaced relation to the spring head, the clamping projection terminating in a manually depressible depending lever arm 46 adjacent to and spaced from the handle column 23.

In Figs. 3 and 10, it will be seen that the ledge portion 42 of the clamping arm 41 is provided at each longitudinal end with a downturned clamping projection 47 provided with an inclined rearwardly extending camming edge 48 for engagement with the blade shoulders 33 to retract the butt edge of the blade into fully retained position under the clips 26.

The operation of the hereinbefore described 50 safety razor will be evident to those skilled in the art. It will be seen that the substantially cylindrical split spring-sleeve head 36 urges the clamping arm 41 against the fixed clamping element 25 to confine the blade 27 therebetween. 55 More particularly, the blade 27 is confined at its rearmost butt portion 34 beneath the lug clips 26 of the portion 25, with the blade being retained to underlie the clips by means of the downturned retaining ears 47 formed on the clamping arm 41. The camming edges 48 of the projections 47 serve to retract the blade into shaving position beneath the lugs 26 and to retain the blade in such position at all times when in use. Inasmuch as each of the clamping members 25 and 41 is retained between the split edge of the resilient razor head, the razor head itself serves to urge the blade into securely clamped position through the medium of the camming surfaces 48 in cooperation with the shoulders 33 formed on the blade 27.

Removal of a blade from clamped position within the razor head is easily accomplished by mere movement of the lever arm 46 toward the handle 21, as illustrated in Fig. 3 of the drawings. 75 The opening movement of the arm causes pivot-

ing of the movable clamping element 41 about a fulcrum defined at the head aperture 45, resulting in deformation of the razor head and the removal of the clamping arm projections 47 from their position in abutment with the shoulders 33 to release the blade from its clamped position to facilitate removal. It will readily be seen that the utilization of the rivet 35, together with the nesting arcuate configuration of the handle portion 24 and of the spring head 36, serves to rigidly connect the head to the handle, while the resilient support of the clamping arm 41 by the spring head 36 prevents displacement of this arm when the device is in use.

The clamping head is entirely open to the flow of water or other cleaning fluid through the head. Water flow is accommodated by the open ends of the spring head and the openings 48 in the end plates 39, so that cleaning of bristles, shaving soap, and the like, from the interior of the razor and the maintenance of the razor in sanitary condition is readily accommodated without necessitating removal of the blade following each shave.

In the modifications of Figs. 12 and 13, the razor is substantially the same as hereinbefore described in connection with Figs. 1-11, inclusive, and identical deformation of the razor head and reference numerals refer to identical portions of the razor. In Fig. 12 it will be noted that the spring head 36' serves substantially the same purpose as the head hereinbefore described. However, in this instance the head is not truly cylindrical in configuration, but rather is provided with opposed flat sides. In the embodiment of Fig. 13, the head 36'' has been slightly modified from its original cylindrical configuration with the top portion only of the head being deformed from arcuate configuration to lie substantially parallel to the clamping arm portion 41 extending through the interior of the head.

In the modification of Fig. 14, some revision of the head and supporting structure has been made. In this figure, the handle supporting post 23 is provided with an upper offset portion 23a which lies substantially parallel to an extended terminal portion 23b which has integrally formed therewith the supporting plate 23c similar in function and design to the fixed clamping element 25 of the structures of Figs. 1-13. The supporting plate 23c is provided with an elongated interior slot 23d, adjacent and below the cutting edge of the blade 27, substantially similar to the slot 29 hereinbefore described. The portion 23b also carries on opposite ends upturned side flanges 23e each having an aperture 23f through which water may flow to facilitate cleansing. The spring head 36a of this type of razor is riveted, as at 36b, to the terminal 23b of the portion 23a, and the spring head has upwardly deflected lug portions 36c beneath which the rear butt edge 34 of the blade 27 is confined. The spring head 36a serves to urge clamping arm 41 into extended surface engagement with the blade 27 to confine said blade therebetween, as hereinbefore fully described, and the arm 41 is provided in similar manner with a terminal actuating lever portion 46.

It will thus be seen that, in the form of the invention shown in Fig. 14, the only major difference resides in the employment of a semi-cylindrical spring head having lugs 36c formed integrally therewith, rather than having the lugs

formed integrally with the supporting portion 25 of the post 23 hereinbefore described.

It will be noted that the razors of the present invention may be economically produced by the utilization of sheet metal stampings for substantially all portions of the razor. The assembly is simplified, particularly since only one fastening means, i. e., the rivet 35 or 36b, is necessary to secure the complete device in assembled relation. The entire effective length of the blade cutting edge 39 is utilized, inasmuch as clamping of the blade occurs at points laterally displaced beyond the length of the cutting edge, and the ready flushing of water through the razor to remove bristles, soap and the like is facilitated without deteriorating the resilient characteristic of the blade-holding heads.

It will be understood that modifications and variations may be effected without departing from the scope of the novel concepts of the present invention as defined in the claims appended hereto.

I claim as my invention:

1. In a razor, a fixed blade clamping element having spaced lugs, a movable blade clamping element having forwardly located camming surfaces projecting therefrom toward said fixed clamping element and a rearwardly projecting actuating arm, a razor blade interposed between said elements and having one edge confined by the lugs of said fixed clamping element and shoulders spaced from said one edge for receiving thereagainst the camming surfaces of said movable element, and resilient spring means biasing said clamping elements toward one another and into contact with said blade, said spring means providing a fulcrum about which said actuating arm is operable to oppose the biasing force of said spring means.

2. In a razor, a pair of relatively movable clamping elements, one of said elements having lugs struck therefrom and the other of said elements having a camming surface and an elongated lever arm portion spaced therefrom, a blade insertable between said clamping elements with one edge portion retained by said lugs and an opposing edge portion engaged by said camming surface, and a split resilient sleeve urging said clamping elements together with said blade confined therebetween and restrained against movement by said lugs and said camming surface, said sleeve contacting said other of said elements adjacent the camming surface thereof and also at the lever arm portion thereof to provide a fulcrum about which said arm is movable against the biasing force of said sleeve to remove said camming surface from engagement with said opposing surface of said blade.

3. In a razor, a fixed blade clamping element having a pair of lugs struck therefrom, a movable clamping element having camming projections extending toward said fixed clamping element in spaced relation to said lugs, a blade having a blunt edge confined by said lugs and an opposing sharpened edge provided with terminal shoulders extending parallel thereto, and a resilient spring head contacting both of said elements and enclosing the movable clamping element to urge the same against said blade to confine the blade against said fixed clamping element, said spring head urging the camming projections of said movable clamping element against the blade shoulders to retain the blade blunt edge against said lugs, to position the blade cutting edge in cutting position.

4. In a razor, a fixed clamping element having a terminal guiding lip and blade clamping lugs struck therefrom opening toward said lip, a movable clamping element overlying said fixed clamping element and having depending camming projections, a razor blade interposed between said clamping elements, said blade having one longitudinal edge inserted between said lugs and said fixed clamping element and having an opposed longitudinal sharpened edge immediately overlying said guiding lip, and resilient means including a longitudinally split inherently resilient clip having the split edges thereof contacting said clamping elements and urging said movable clamping element into engagement with said blade with the depending camming projections engaging said blade adjacent said sharpened edge and urging said one edge beneath said lugs.

5. A razor comprising a handle, a spring-clip head of substantially cylindrical or loop-shaped cross section secured to said handle and having a radial slot therein, a fixed clamping member carried by said handle and projecting radially across the interior of said head to project through said slot, lugs deformed from that portion of said fixed clamping member in the interior of said head, a movable clamping member also projecting across the interior of said head and having an attenuated actuating portion depending therefrom in closely spaced relation to said handle, dependent camming ears formed on said movable clamping member, and a razor blade interposed between said clamping members with one longitudinal blade edge confined beneath the lugs of said fixed clamping member and the opposing longitudinal edge being provided with recessed terminal shoulders against which the camming projections of said movable clamping member are urged by said resilient head to retain said blade between said clamping members.

6. A safety razor comprising an inherently springy head of normally cylindrical or loop-shaped cross section, split lengthwise along one side and having circumferentially spaced longitudinal apertures in its opposite side in angular relation to the lengthwise split; a fixed blade support member having upwardly extruded forwardly extending blade retaining clips in spaced longitudinal relation; a movable clamping member having rearwardly inclined down turned lateral camming projections disposed immediately forward of the lengthwise split, said members traversing the interior of said head and having ledges projecting forwardly through and beyond the lengthwise split of said head and normally

urged together thereby in clamping relation; an attenuated extension projecting rearwardly through and beyond the aforesaid apertures from each of said members to provide an actuating arm for the movable clamping member and a handle connection from the fixed support member; and a single-edged blade removably fitting between the ledges of the said members and having offset ends forming a shoulder rearwardly of the ends of the cutting edge thereof for engagement with said camming projections to retractively adjust and lock the blade in shaving position between said members with the butt edge thereof fully retained under said clips upon said members being urged into clamping relation by said head.

7. A safety razor according to claim 6 wherein the attenuated extension of the fixed support member is adapted to connectably secure the support member and razor head rigidly to said handle.

8. A safety razor according to claim 7 wherein the actuating arm extension of the movable member is fulcrumed on the upper edge of the circumferential space between said apertures whereby manual actuation thereof relatively to the handle is accommodated causing deformation of the razor head in opposition to its inherent biasing action to release the blade for removal.

9. A safety razor according to claim 8 wherein the ledge projection of the fixed support member is formed along its forward longitudinal edge to provide a face guard, and immediately adjacent to said guard in parallel relation is an elongated slot through which beard-ladened-lather is expelled during a shaving operation.

GLENN T. RANDOL.
